UNITED STATES PATENT OFFICE.

HENRY A. BATES, OF MIDDLETOWN, CONNECTICUT, AND LEVI J. LABRUM, OF ALBANY, NEW YORK, ASSIGNORS TO THE SUMMIT THREAD COMPANY, OF EAST HAMPTON, CONNECTICUT, A CORPORATION OF MAINE.

CONE-THREAD-HOLDER SUPPORT.

SPECIFICATION forming part of Letters Patent No. 734,293, dated July 21, 1903.

Application filed November 21, 1902. Serial No. 132,191. (No model.)

To all whom it may concern:

Be it known that we, HENRY A. BATES, residing at Middletown, in the county of Middlesex and State of Connecticut, and LEVI J. LABRUM, residing at Albany, in the county of Albany and State of New York, both citizens of the United States, have invented an Improvement in Supports for Cone Thread-Holders, of which the following is a specification.

10 Heretofore cones of thread wound upon a hollow paper form have been employed in connection with sewing-machines. These have for use been placed in an upright position, and efforts to hold the same in a more advantageous and horizontal position have not heretofore met with success.

Our invention relates to a combined stand and support for a cone thread-holder, together with which a guide for the thread is advantageously but not necessarily employed. This stand is constructed for attachment to a suitable bed or table, and the support for the cone thread-holder is in the form of a horizontal bracket extension of the stand at right angles 25 and attached firmly thereto or preferably integral therewith.

The construction we prefer is an integral casting comprising a foot portion and upright in the stand and an integral bracket extension 30 in the form of four radial tapering ribs, the rib edges at their greatest diameters being serrated or toothed to engage the inner surface of the cone thread-holder, which is hollow and formed of straw or pasteboard. The 35 guide in the form of a wire is removably secured at one end to the upper end of the stand, and the other end is bent at a right angle, terminating in an eye or loop for the thread coinciding with the imaginary prolongation of the center of the bracket extension.

In the drawings, Figure 1 represents by a perspective view our improvement. Fig. 2 is a side elevation and section of the cone thread-holder in place. Fig. 3 is a cross-section of Fig. 2 at $x-x$, and Fig. 4 illustrates by a longitudinal section and partial elevation a modified form of our invention.

Referring to Figs. 1 and 2, a represents the foot portion of trefoil form, a' the upright, and a^2 the bracket extension. These parts

are advantageously and preferably of one integral casting, the foot portion being provided with screw-holes 1 for firmly attaching the structure to a suitable bed or table. The bracket extension a^2 is at right angles to the upright a' and preferably comprises the structures shown in Figs. 1, 2, and 3, which consist of four radial tapering ribs 2, 3, 4, and 5, the parts of which may be reduced midway in their length for the purpose of lightening 60 the structure and occupy a horizontal position. The rib edges at their greatest diameters and adjacent to the upright a' are serrated or toothed at 6, so that when the cone b , of straw or pasteboard, is placed over the 65 bracket extension and forced along to a seat thereon said teeth or serrations are slightly embedded in the comparatively soft inner surface of said cone, engaging the same and preventing accidental removal. A surface of 70 thread c is wound upon this cone. d represents the thread-guide, of wire, one end of which passes through a perforation in the upper end of the upright a' and is clamped thereto by a screw 7. The other end of the 75 thread-guide d is bent at right angles to the main portion and terminates in an eye or loop 8, the center of which coincides with the imaginary prolongation of the center of the bracket extension a^2 . From this construction 80 it will be observed that the thread of the cone thread-holder in passing through the eye of the thread-guide may be drawn off evenly from the cone thread-holder at all points of the circumference of the cone 85 thread-holder, so that the drawing-off tension is approximately equal at all times, and it will be further apparent that the thread in passing off in this horizontal direction may pass directly to the machine, it not being necessary, as heretofore, to carry the thread up, across, and down to the machine, as has been the case where the cone thread-holders have occupied a vertical position.

In the form of our invention shown in Fig. 95 4 the rod e is secured in any desired manner to and at right angles to the standard. A centering-frame e' , in the form of a ring, and radial arms are secured to the rod e , and wire spring-arms f , in approximately the form 100

shown and with tapering members, are secured to the free end of the rod *e*, preferably as shown, by passing through apertures in the rod, and parts thereof being bent down 5 into close proximity and contact with said rod. The tapering or spring portions of said arms approximately agree with the inner surface of the cone thread-holder, so as to simultaneously act as a support therefor and to 10 produce a binding-friction, preventing accidental removal.

We claim as our invention—

1. A support for a cone thread-holder, comprising a foot portion, an upright, and bracket 15 extension at right angles to the upright, and all of said parts integral, and the bracket extension consisting of integral tapering portions in planes at right angles to one another, the central longitudinal parts of which are 20 removed, so that bearings are formed at the respective ends of said tapering portions and adapted to receive and contact with the inner surface of the cone thread-holder and support the same in a horizontal position.
- 25 2. A support for a cone thread-holder, comprising a foot portion, an upright and bracket extension at right angles to the upright and the bracket extension consisting of tapering portions in planes at right angles to one another the central longitudinal parts of which are 30 cut away so that bearings are formed at

the respective ends of said tapering portions, and serrations or teeth on portions of the edges of said tapering parts so formed as to engage the inner surface of the cone thread- 35 holder to support the same in a horizontal position and prevent its withdrawal.

3. A support for a cone thread-holder, comprising a foot portion, an upright and horizontal bracket extension at right angles to the 40 upright, the bracket extension having a bearing for the cone thread-holder at the larger end of said cone thread-holder and tapering portions in planes at right angles to one another, forming separated points of bearing 45 support at the smaller end of the cone thread-holder, so that bearings are formed for the cone thread-holder adapted to receive and contact with the inner surface thereof at the respective ends and support the same in a 50 horizontal position.

Signed by us this 13th day of November, 1902.
